UNITED STATES PATENT OFFICE.

LEO HIRSCHFELD, OF NEW YORK, N. Y., ASSIGNOR TO STERN & SAALBERG COMPANY,
OF NEW YORK, N. Y.

DESIGN FOR A PAPER DISPLAY-BOX.

47,228.

Specification for Design.

Patented Apr. 13, 1915.

Application filed September 29, 1914. Serial No. 864,170. Term of patent 14 years.

To all whom it may concern:

Be it known that I, LEO HIRSCHFELD, a citizen of the United States, residing at New York, borough of Manhattan, in the county and State of New York, have invented a new, original, and ornamental Design for a Paper Display - Box, of which the following is a specification, reference being had to the accompanying drawing, forming part thereof.

The figure is a perspective view of a paper box, showing my new design.

I claim:

The ornamental design for a paper display box, as shown.

LEO HIRSCHFELD.
